UNITED STATES PATENT OFFICE.

EMIL A. BRINER, OF EAST ORANGE, NEW JERSEY.

SYSTEM OF AIR DISTRIBUTION.

1,298,655.

Specification of Letters Patent.

Patented Apr. 1, 1919.

Application filed August 8, 1916. Serial No. 113,841.

To all whom it may concern:

Be it known that I, EMIL A. BRINER, a citizen of the United States, residing in East Orange, county of Essex, and State of New Jersey, have invented certain new and useful Improvements in Systems of Air Distribution, of which the following is a specification.

This invention relates to the conveyance and distribution of air or other gases under pressure and among its objects are to improve the distribution and regulation of the air at discharge outlets; to secure a substantially uniform distribution of air throughout an outlet area of considerable length; to direct the outflowing air in such a way that the emerging currents shall be directed in proper lines; to produce a slight resistance at the outlet in such a manner as to make the discharge uniform without seriously impeding the velocity; and to increase the efficiency of air ducts or pipes, so as to avoid losses resulting from bends and to obtain a greater flow of air with the expenditure of less power.

The nature and more specific objects of the invention will appear from the following detailed description of certain preferred embodiments thereof.

In the accompanying drawings, which form a part of this specification—

Figure 1 is a fragmentary plan view partly in horizontal section of parts of an air system embodying my invention and showing the same applied to a paper drying machine.

Fig. 2 is a front elevation of parts of the structure shown in Fig. 1.

Fig. 3 is a sectional view on line III—III of Fig. 1.

Fig. 4 is a transverse sectional view showing an air distributing duct.

Fig. 5 is an elevation of a portion of the duct shown in Fig. 4.

Fig. 6 is a diagrammatic sectional view partly in side elevation and partly in section of the duct shown in Fig. 5 and illustrating the current of air impinging upon the paper on one of the drying rolls.

Fig. 7 is a diagrammatic sectional view of the same.

Fig. 8 is a fragmentary sectional view of a distributing duct illustrating a modified construction.

Figs. 9 and 10 are side elevations of different forms of deflector strips. 55

Fig. 11 is a view of a construction applicable to the distribution of air from long ducts.

Fig. 12 is a cross-sectional view of a modified construction showing deflector strips applied interiorly of the duct. 60

Fig. 13 is a cross section of a portion of a rectangular duct showing a deflector strip applied thereto. 65

For purposes of illustration, I have shown my invention in connection with a system of supplying hot, dry air to paper drying machines as it has particular advantages when utilized in this connection, but it is to be understood that my invention is not limited to this use. 70

Referring to the drawings in detail, the numeral 1 designates a series of drying rolls over which passes the web of paper 2. These rolls are arranged to be driven in any suitable manner as by the gearing 3, the side of the machine upon which the gears are mounted being known as the back of the machine, while the other side is the front 75

and is where the machine tenders stand. A current of air dried and heated in any suitable manner is forced through a main duct 4 by a fan (not shown) or otherwise, and is delivered to headers 5, which extend along 80

the back of the machine and from which lead branches 6. From the branches lead cross-arms or distributing pipes 7, which are suitably disposed in proximity to the paper on the drying rolls. Heretofore these 85

distributing pipes have been provided with perforations or long slots through which the air has issued, but owing to the velocity of the air and its movement in the pipes from the back toward the front of the machine, it has issued from these orifices in a 90

diagonal direction toward the front of the machine and as it has not been directed against the paper web to be dried in the most effective manner, a large part of the 95

air has escaped to the front of the machine sometimes without uniformly drying the sheet of paper. The issuance of the hot air and vapor at the front of the machine has also been very objectionable as producing 100 an almost intolerable condition of heat to which the operators have been subjected. 105

I have overcome these difficulties by pro-

- viding an improved means of distribution by which the air currents are caused to issue with a great degree of uniformity throughout the entire length of the distributing pipes and by the use of which the currents are caused to impinge directly upon the paper web as nearly normal thereto as may be desired, the currents being preferably directed slightly backward, so as to be discharged with the vapor from the web at the back of the machine instead of at the front. In this way, most efficient drying is secured and at the same time the operators are protected from the blasts of hot air and vapor.
- 15 I accomplish these results by the use of deflectors so-shaped and arranged as to divert the forward velocity of the air and convert it into a velocity at right angles or slightly reversed from the direction in which the air 20 enters the distributing pipes. Preferably I make these deflectors in the form of strips 15 of cast or other metal, which are provided with deflector blades 16, which are spaced apart sufficiently close to prevent the 25 forwardly progressing air currents in the pipe from issuing directly and retaining their velocity in the original direction. These blades may be of any suitable shape, such, for instance, as the reversely curved 30 or crescent shape shown in Figs. 6 and 9, or they may be rearwardly inclined, as shown in Fig. 10. In addition to performing their deflecting functions, these strips may desirably constitute structural parts of the 35 pipe which may be made of a sheet metal shell having its edges joined along a longitudinal line by the strips. As illustrated in Figs. 4, 5, 6, and 7, the pipe comprises the shell 17 having the downwardly turned 40 flanges 18 between which are secured the strips 15 in any suitable manner as by the bolts 19. If desired, a damper construction may also be employed for partly or wholly closing the outlets. As illustrated, the 45 flanges 18 are provided with the outwardly turned small flanges 20, upon which is slidably mounted the sheet metal damper 21. In Fig. 8, I have illustrated a modified construction in which the flanges on the pipe 50 shell 18 are omitted, the strip 15 being provided with flanges 22, which may be riveted or otherwise secured to the edges of the shell. Other constructions may obviously be employed, such as with the deflector strips 55 wholly within the contour of the pipes, as shown in Fig. 12, or the deflector strips may be utilized in a rectangular duct as shown in Fig. 13. The deflector strips are preferably made in suitable lengths having their ends 60 so shaped that they may be fitted together end to end to produce any length desired; thus the strips shown in Figs. 9 and 10 have convex ends 23 and concave ends 24, which are adapted to fit the concave and convex 65 ends respectively of adjacent strips. In the

constructions illustrated, it will be seen that the strips and deflector blades are of considerable depth and thickness, this dimension being nearly as great as the distance between the blades.

70 In Fig. 11, I have illustrated the use of my deflectors in connection with a long pipe such as may be employed for distributing hot, dry air near the roofs of factory buildings in which steam or other vapors arise or 75 which may be employed in drying rooms or the like.

75 My construction of deflector strips makes possible of provision at very low cost of distributing pipes of any length provided 80 throughout all or a greater part of their extent with distributing orifices. My construction also secures a very considerable degree of uniformity in the emission of air throughout all parts of the pipe. In this 85 way a much greater degree of uniformity of distribution is secured than is possible with the use of spaced nozzles or other means and the drying air is therefore employed much more efficiently. Fig. 11 also shows how two 90 or more of my strips may be mounted side by side, so as to increase the outlet area when this is desired. Thus it will be seen that by the use of a standard size deflector 95 strip, any extent of opening necessary may readily be obtained.

95 In addition to providing improved means for distributing air at outlets, I have devised a novel construction for bends, such as T's and elbows, which may be employed in 100 ducts for fluid distribution to secure greatly increased efficiency thereof. Ordinarily in air ducts and the like, especially in the larger sizes, considerable losses in efficiency result from the passage of the air through the various bends, this being probably due to the fact that the air currents when passing around the bends do not remain uniformly distributed throughout the area of the pipe 105 but pile up, so to speak, against the outer walls of the bends, thereby increasing the velocity of the air at those points, increasing the skin friction and producing at and immediately beyond the bends, eddy currents 110 which dissipate the velocity of the air. I 11 overcome these difficulties and secure greatly increased efficiency by providing means for dividing up the area of the duct at the bends, so as to secure a more uniform distribution 115 of the air at these points and to prevent or diminish the formation of eddy currents. I have illustrated this construction in Figs. 1 and 3, in which 30 are elbows and 31 is a T embodying my improved construction. It 120 will be seen that the elbows are divided by a plurality of septa or diaphragms 32 into a plurality of separate passages 33 through which the air must pass in rounding the curves, the several currents thus produced 125 not being able to interfere with each other 130

and set up eddy currents, it being impossible for all of the air to be accelerated in the outer portion of the elbow as in previous constructions. The T 31 is provided with similar septa 34, which act in like manner. By the use of this construction, a larger volume of air may be conveyed through a duct of a given cross-section, at the expenditure of the same power at the fan or less power may 10 be utilized to drive an equal volume of air through a duct than if the improved construction is not used.

While I have shown and described in detail, certain preferred embodiments of my 15 invention, these are to be understood as merely illustrative of the principle thereof and I do not desire to limit myself therefore to these specific embodiments.

At various points in this specification and 20 in the claims, I have referred to air as the fluid to be conveyed or distributed, but obviously my invention is not limited to dealing with air only and I desire this term to be understood as including air or any other 25 fluid capable of being dealt with in accordance with my invention.

Having thus described my invention what I claim as new herein and desire to secure by Letters Patent is:

30 1. In a system of air distribution, the combination of a pipe, having a longitudinal slot therein and a series of deflectors arranged transversely in said slot.

2. In a system of air distribution, the 35 combination with a pipe having a longitudinal slot therein, of a series of deflectors arranged transversely in said slot, said deflectors being located outside of the circumferential area of the pipe so as not to 40 diminish the effective cross-section thereof.

3. In a system of air distribution, a pipe having a longitudinal series of outlet orifices therein and deflectors associated with said outlet orifices for directing currents of air 45 outwardly from said pipe and rearwardly with respect to the direction of the flow of the air through the pipe.

4. An air distributing pipe including a shell having spaced longitudinal margins 50 providing a slot and a deflector strip mounted in said slot and forming a spacing piece for the shell margins.

5. A deflector strip for air distributing pipes comprising side walls united by a plurality of transverse deflector blades.

6. In an air distributing system for web

drying machines, the combination with a system of drying rolls, of distributing pipes extending transversely of the rolls and deflecting means at the outlets from said pipes 60 for directing the air currents toward the web on the rolls and rearwardly toward the back of the machine.

7. In a system of air distribution a pipe having a bend at an intermediate portion of 65 its length, a plurality of septa extending transversely across the bend and following the curvature thereof to divide the bend into a plurality of curved air passages separate from one another in the direction of the radius of the bend, whereby the velocity of the air entering the bend from the straight portion of the pipe will be undiminished in its passage through the bend and the remaining length of the pipe. 75

8. In a system of air distribution, a pipe having a bend intermediate of its ends, a plurality of septa located in the bend and spaced from each other so as to provide a plurality of air passages of equal width, 80 each conforming to the curvature of the opposite walls of the bend, whereby the air passing through the bend will be equally distributed throughout the entire area thereof, and will traverse the remaining portion 85 of the pipe with the same volumetric efficiency which it possessed prior to entering the bend.

9. In a system of air distribution, a pipe having straight portions and a bend intermediate of the straight portions and connecting the same, a plurality of septa located within said bend and spaced from each other, said septa conforming to the curvature of the opposite walls of the bend 95 and forming a plurality of curved air passages of equal width and substantially equal lengths in said bend, whereby the air entering said bend from one straight portion of the pipe will be evenly distributed 100 throughout the entire area of the bend in its passage therethrough, and will enter the remaining straight portion of the pipe without loss in the volumetric efficiency possessed by it in traversing the first straight 105 portion of the pipe.

10. In a system of air distribution, a pipe having an orifice in the wall thereof and a plurality of like deflectors disposed transversely of said orifice.

EMIL A. BRINER.
